UNITED STATES PATENT OFFICE.

SAMUEL G. WORTON, OF DUQUESNE, PENNSYLVANIA.

SOAKING-PIT FURNACE.

Application filed February 2, 1928. Serial No. 251,401.

This invention relates to soaking pit furnaces and more particularly to an improved bottom structure for this class of furnaces and has for its object the provision of an improved form and composition of bottom lining which will be more or less permanent and will replace the beds of coke breeze heretofore used to cover the bottom of the pits of such furnaces, and which have to be replaced every twenty-four hours when the furnaces are in use.

Another object is to provide a hard and substantially permanent bottom lining over which the molten cinder collected in the furnace pits will flow so as to permit the collecting of said cinder from which a considerable quantity of iron may be recovered.

With the coke breeze beds or linings heretofore used no cinder can be recovered since it is mixed with a large amount of coke breeze, prohibiting its use in either the blast furnace or the open hearth furnaces.

In the drawings:

25 Figure 1 is a longitudinal sectional elevation through a furnace constructed in accordance with this invention.

Figure 2 is a transverse section taken on the line II—II of Figure 1.

30 Figure 3 is an elevation showing the means for operating the slag hole closures.

Referring more particularly to the drawings, the letter A designates the furnace as a whole, which is divided by the usual walls to form regenerator chambers 2 and 3, a bank of pits 4 and a cinder tunnel 5.

40 The bottoms of the pits 4 are supported on beams 6 and each is composed of a bottom casting 7 supported on the beams 6 and a layer of brick 8 is laid over the casting 7. The side walls of each of the pits 4 are also formed from brick, as usual.

45 The bottom casting 7 is provided with a centrally arranged slag discharge port 9 which communicates with a port frame 10 supported on the beams 6 and closed at its lower end by a hinged closure 12. The closures 12 are connected to operating cables 13 by levers 14 so that each of said closures 50 may be opened and closed by operating the drums 15 to which the cables are connected. Each of the drums 15 is provided with an individual worm and worm-wheel operating mechanism 16.

55 The bottom portion of each of the pits 4

is provided with a protective substantially or semi-permanent refractory lining 18 which extends from a point on the side walls in line with the bottom of the ports 19, connecting pits with the regenerators, 60 downwardly to the brick bottom wall 8 and across the bottom wall 8.

The lining 18 is thinnest or of least depth at its upper edge and increases in thickness or depth downwardly to the point of junction of the bottom and side walls of the pit and then is gradually thinner or of less depth from the side walls inwardly to the slag port at the center of the bottom so that the molten cinder or slag will drain over 70 the bottom lining and out through the port 9.

In actual practice I have found that a lining having a thickness of approximately two inches at its upper edge and increasing 75 to approximately seven inches at the junction of the side and bottom walls, and then tapering over the bottom wall to about six inches at the discharge port 9, gives good 80 results.

The lining may be composed of mixtures of various refractory materials, however, I have found that very good results are obtained from a lining composed of a mixture 85 of calcined dolomite, crushed to lumps of one-half inch or less, finely divided or ground open hearth cinder and tar. The calcined dolomite forms a durable, refractory base, the finely divided open hearth cinder filling up the interstices and the tar 90 serving as a binder to bond the mixture together.

The slab or cinder port 9 is, of course, continued up through the bottom brick wall 8 and the lining 18 and is adapted to be 95 plugged when the pit is in use by first covering the door or closure 12 with a layer of loam 20, and then filling the remainder of the port with a body of coke breeze 21 which is preferably mounded up slightly above the 100 lining 18 and covered with a layer of raw dolomite 22.

When it is desired to draw off the cinder or slag it is only necessary to open the closure 12 and poke the plugging material in the port 9 slightly to loosen the same and the cinder or slag will immediately run out due to the slope of the lining 18 and the hard nature of the lining.

105 The lining 18 is substantially permanent 110

and has a life of a year or more, while the coke breeze bottom lining heretofore used had to be entirely remade every twenty-four hours. Furthermore, the slag or cinder dis-
5 charged through the ports 9 when the lining 18 is used is not mixed with coke breeze as it is when the coke breeze bottom lining is used, and therefore, this slag or cinder has a commercial value since it can be
10 charged into either open hearth or blast furnaces to recover its iron content of from 55 to 70 per cent.

While I have shown and described a specific embodiment of my invention it will be
15 understood that I do not wish to be limited thereto since various modifications may be made without departing from the scope of my invention as defined in the appended claims.

20 I claim:

1. The combination with a soaking pit furnace having each pit provided with brick bottom and side walls and a centrally arranged slag hole opening through said bottom wall, of a semi-permanent refractory lining on the bottom of said pit and extending upwardly along the side walls there-
25 of, said lining being of least depth at its upper edge and having its greatest depth
30 at the junction of the side and bottom walls of said pit, and being of slightly decreasing depth from the side walls of the pit toward the center of said pit so as to form an inclined bottom over which the slag will
35 flow to said slag hole, said slag hole being normally closed at its lower end by a remov-

able closure and filled to a point above the level of said lining with coke breeze and having a covering of dolomite.

2. The combination with a soaking pit fur-
nace having the usual pits provided with brick bottom and side walls and a centrally arranged slag hole opening through said bottom wall, of a semi-permanent refractory lining on the bottom of said pits and ex-
40 tends upwardly along the side walls thereof, said lining having its bottom wall inclined toward said slag hole so as to permit the slag to flow from the pit by gravity, said slag hole being normally closed at its lower end by a removable closure and filled to a point above the level of said lining with a granular filling material.

3. The combination with a soaking pit fur-
nace having the usual pits provided with brick bottom and side walls and a centrally arranged slag hole opening through said bottom wall, of a semi-permanent refractory lining on the bottom of said pits and ex-
45 tends upwardly along the side walls thereof, said lining having its bottom wall inclined toward said slag hole so as to permit the slag to flow from the pit by gravity, said slag hole being normally closed at its lower end by a hinged closure and filled to a point above the level of said lining with a granular filling material, at least the upper ex-
50 posed face of said filling material being composed of refractory material.

In testimony whereof, I have hereunto signed my name.

SAMUEL G. WORTON.
